UNITED STATES PATENT OFFICE.

HARRY SPIRO, OF CHICAGO, ILLINOIS.

DENTAL CASTING FLASK.

Application filed August 28, 1926. Serial No. 132,211.

This invention relates to improvements in casting flasks generally, and more especially to that type of flask frequently used in dental laboratories for the casting of 5 bridges, crowns, fillings, inlays, plates and the like.

In the practice of dentistry, the casting of gold, aluminum, and other metals and alloys is accomplished by the preparation 10 of molds for each individual cast, wherein an investment, such as plaster or other mold-forming material, is placed in a flask in plastic state, and a pattern having the form of the article to be produced is embedded 15 within the same, the pattern being made of a volatile substance, such as wax or the like, which will be destroyed by the action of heat applied to the flask for the purpose of melting it and for the driving from the investment of all of its moisture content. When 20 properly heated, the investment will harden and the wax pattern be destroyed whereby a mold-space or cavity will be provided for the reception therein of the desired molten 25 metal from which the article is to be produced, and this molten metal has to be forced into the mold-space or cavity, and is accomplished either by the use of an application 30 of pressure to the top of the flask, or a vacuum to the underside. While I have here shown the particular embodiment of 35 my invention as adapted for use in connection with the application of pressure, it is to be understood that it is equally well adapted for use with suction.

In cases where pressure is used for forcing the molten metal into the mold-space or cavity, such pressure may be applied in a variety of ways. For example, a pressure 40 machine may be used adapted to furnish air or other gas under pressure to the top of the flask above the molten metal. Pressure also may be applied by hand, by covering the top of the flask with several sheets of wet 45 blotting paper held firmly in place. By this method, steam is generated beneath the blotting paper furnishing pressure above the molten metal in the flask to force the metal downwardly into the mold-space or cavity.

When hardened, the investment is rather porous, and, in the use of a pressure machine, or if pressure is furnished by means of wet blotting paper, or in any other 55 manner, the molten metal is forced down-

wardly through the sprue hole leading into the mold-space or cavity, under the action of such pressure, the air in the mold-space or cavity escaping into the pores of the investment. In the use of a vacuum applied to 60 the lower end of the flask, the action of the same draws the air out of the mold-space through the pores in the investment, with the result that the molten metal is forced into the mold-space or cavity under atmospheric pressure.

In the hardening and drying of the investment in the flask while setting, and also in the heating of such investment for the purpose of driving out its moisture content and 70 rendering it porous, such investment shrinks to a certain extent. The heating of the flask also causes a certain expansion of the flask. Such resulting shrinking of the investment and expansion of the flask causes 75 a separation between the outer wall of the flask and the investment, leaving a crack or air space therebetween. One of the defects of many flasks as heretofore made was the presence of such a crack which permitted the escape of air therethrough, with either the pressure or vacuum system. One 80 of the features of my invention, is the provision of novel means for preventing such escape of air. By the use of my invention, such escape around the sides of the investment is prevented, and the pressure is directed to the region of the sprue hole and directly over the mold.

My improved flask is also strong and durable, simple and cheap to construct, and easy to operate. Other features and advantages of my invention will appear more fully as I proceed with my specification.

In that form of device embodying the features of my invention shown in the accompanying drawings, Fig. 1 is a vertical sectional view showing the casting flask inverted with the wax pattern in place in the investment, and Fig. 2 is a similar view 100 showing the flask right side up with the wax pattern and sprue wire removed, and molten metal poured into the investment.

As shown in the drawings, 10 indicates a substantially cylindrical flask preferably 105 having an outwardly turned flange 11 at the bottom in order to give the same a steadier base. The upper edge of the cylindrical wall is bent inwardly and downwardly as indicated at 12, and its inner edge is bent down- 110

wardly to form the inner depending concentric ring 13 lying inside of and parallel with the outer wall 10 of the flask.

- In the practice of the invention, the flask 5 is inverted as shown in Fig. 1 on the top of a work bench or other suitable support (not shown) and is centered over a hopper or sprue wire support 14, which is circular in form and has a convex upper face provided 10 with an opening at its center. The member 14 carries supported therein a sprue wire 15 upon the upper end of which is supported the wax pattern 16 of the object to be cast. The flask is then filled with a suitable mold- 15 forming material or investment, such as plaster, 17, in the plastic state. After the investment has dried and set, the flask is turned right side up, and the member 14 and the sprue wire 15 removed. 20 Heat is then applied to the flask for the purpose of thoroughly drying the investment and driving all moisture therefrom, and for the destroying, melting, or vaporizing of the wax pattern 16. 25 After the investment 17 is thoroughly dried and preferably while the flask and investment are still in a heated condition, molten material such as, for example, molten gold 18 is poured in the conical top of the investment. While the parts are still heated 30 and the metal is still molten, pressure is applied to the upper end of the flask. This may be accomplished, for example, by means of an air pressure machine of any ordinary type. For example, 19 may indicate the 35 pressure head of such a machine, which is adapted to engage with the upper edge of the flask, such upper edge being preferably ground, or a suitable gasket being provided, 40 so that the pressure head will co-operate with the upper edge of the flask in a well known manner. The application of the pressure forces the molten material 18 down into the mold cavity as indicated by 18°. 45 The particular feature of the invention is the provision of the inner ring 13, which prevents the escape of pressure from the top of the flask between the investment and the outer wall of the flask. As stated before, in 50 the drying and heating of the investment and flask, the investment shrinks and the flask expands causing a crack between the investment and the outer wall of the flask. Such shrinking of the investment, however,

causes the same to shrink inwardly tightly 55 around the inner ring 13 thus making an effective seal at this point and preventing any pressure from escaping from the top of the flask to the crack between the investment and the outer wall of the flask. The heating 60 of the flask also may cause an expansion of the inner ring 13. If this is the case, it serves to make the joint between the inner ring 13 and the investment additionally tight. The inner ring 13 is joined to the 65 upper edge of the wall 10 by means of the metal part 12, which obviously is also impervious to air. Consequently, if there is a tight joint between the outer side of the inner ring 13 and the investment, no air can 70 leak from under the pressure head out to the crack or space between the investment and the outer wall 10.

While I have shown and described certain embodiments of my invention, it is to be understood that it is capable of many modifications. Changes, therefore, in the construction and arrangement may be made without departing from the spirit and scope of the invention as disclosed in the appended 75 claims, in which it is my intention to claim all novelty inherent in my invention as broadly as possible in view of the prior art. 80

What I claim as new, and desire to secure by Letters Patent, is:

1. An integrally formed dental casting flask comprising a cylindrical portion having a wide supporting flange at its base, and an inverted cone-shaped sprue-gate at its top terminating in a depending flange forming a 90 short cylinder concentric with the aforesaid cylindrical portion and of relatively large diameter in relation to the sprue.

2. An integrally formed dental casting flask comprising a cylindrical portion having an outwardly flared supporting flange at its base, and at its top, an inverted cone-shaped sprue-gate which terminates in a cylindrical apron concentric with the aforesaid cylindrical portion, and formed by extending the walls of the sprue-gate parallel with the axis of the flask to a considerable extent whereby the sprue-opening may be formed at a point above the lower edge of 100 said apron.

In testimony whereof, I have hereunto set my hand this 23rd day of August, A. D. 1926.

HARRY SPIRO.
